(57) **CLAIM**

The ornamental design for an LED flashlight, as shown and described.

DESCRIPTION

FIG. 1 is a front, top and left side perspective view of an LED flashlight, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a front, top and right side perspective view of an LED flashlight thereof.

The broken line showing of the LED flashlight is for the purpose of illustrating portions of the article and forms no part of the claimed design.

1 Claim, 8 Drawing Sheets
